US00D899359S

(12) **United States Design Patent** (10) Patent No.: **US D899,359 S**
(45) Date of Patent: **** Oct. 20, 2020**

(54) **WIRELESS CHARGING SUPPORT**

(71) Applicants: **Qingsen Zhang**, Guangdong (CN);
Junling Chen, Guangdong (CN);
Jianqiang Liang, Guangdong (CN)

(72) Inventors: **Qingsen Zhang**, Guangdong (CN);
Junling Chen, Guangdong (CN);
Jianqiang Liang, Guangdong (CN)

(73) Assignee: **UGREEN GROUP LIMITED**,
Shenzhen, Guangdong (CN)

(**) Term: **15 Years**

(21) Appl. No.: **29/687,308**

(22) Filed: **Apr. 12, 2019**

(51) LOC (12) Cl. **13-02**

(52) U.S. Cl.

USPC **D13/108**

(57) **CLAIM**

The ornamental design for a wireless charging support, as shown and described.

DESCRIPTION

FIG. 1 is a perspective view of a wireless charging support showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof; and,

FIG. 9 is a perspective view thereof, shown with the ring in an open position.

The broken lines shown depict environment that forms no part of the claimed design.
